US00D679524S

(12) **United States Design Patent**
Corcoran et al.

(10) **Patent No.:** **US D679,524 S**
(45) **Date of Patent:** **** Apr. 9, 2013**

(54) **SEATING UNIT**

(71) Applicants: **Sean M. Corcoran**, East Grand Rapids, MI (US); **Thomas Overthun**, San Francisco, CA (US); **Elger Oberwelz**, San Francisco, CA (US); **James N. Ludwig**, Grand Rapids, MI (US); **David J. Battey**, Caledonia, MI (US); **Nickolaus William Charles Deevers**, Grand Rapids, MI (US); **Keith Robert Machin**, Wyoming, MI (US)

(72) Inventors: **Sean M. Corcoran**, East Grand Rapids, MI (US); **Thomas Overthun**, San Francisco, CA (US); **Elger Oberwelz**, San Francisco, CA (US); **James N. Ludwig**, Grand Rapids, MI (US); **David J. Battey**, Caledonia, MI (US); **Nickolaus William Charles Deevers**, Grand Rapids, MI (US); **Keith Robert Machin**, Wyoming, MI (US)

(73) Assignee: **Steelcase Inc.**, Grand Rapids, MI (US)

(**) Term: **14 Years**

(21) Appl. No.: **29/439,218**

(22) Filed: **Dec. 7, 2012**

Related U.S. Application Data

(63) Continuation of application No. 29/436,741, filed on Nov. 8, 2012, which is a continuation of application No. 12/987,273, filed on Jan. 10, 2011.

(57) **CLAIM**

The ornamental design for a seating unit, as shown and described.

DESCRIPTION

FIG. 1 is a top, front, right perspective view of a seating unit embodying our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line representations in the figures show unclaimed environment, and thus form no part of the claimed design.

The nature of this product is a seat for supporting a human in a seated position.

1 Claim, 7 Drawing Sheets
